SHUTTLE TENSION

Egid Scherdel, Worcester, Mass., assignor to
 Crompton & Knowles Loom Works, Worcester,
 Mass., a corporation of Massachusetts

Application August 3, 1931. Serial No. 554,660

11 Claims. (Cl. 139—215)

This invention relates to improvements in weft tensions for shuttles and it is the general object of the invention to provide a shelf-threading draw-back tension which will be capable of pulling back a large amount of weft when the shuttle comes to rest at the end of its flight.

In certain classes of shuttles for weaving fine fabrics it is desirable to employ a pull-back tension which will take up any slack that results from the rebounding of the shuttle or the forward movement of the lay after the shuttle is boxed. This is particularly true in the use of wefts which are relatively inelastic and also in the weaving of those fabrics where the weft tension must remain substantially uniform. A form of tension which has gone into very extensive use is that employing a set of fixed pins for guides between which play a set of loops bent in a pivoted wire. It is an important object of my invention to provide a tension of this type wherein the end loop is in the form of a spiral trap for the purpose of preventing unthreading.

In tensions of this general class heretofore proposed the movement of the pivoted wire having the loops has been induced by the weft in such a way that the take-up is proportional merely to the movement of the loops between the fixed pins. It is a further important object of my present invention to provide the pivoted member with an actuator arm which is engaged by the weft and is operative to add to the draw-back caused by the movement of the loops with respect to the pins. In this connection I make use of the arm to move the loops into threading position. The arm may preferably move across the path of movement of the weft as the latter moves from one of the pins to the shuttle delivery eye, and the looped wire is preferably though not necessarily pivoted in that part of the tension cavity of the shuttle remote from the bobbin.

With these and other objects in view which will appear as the description proceeds, my invention resides in the combination and arrangement of parts hereinafter described and set forth in the claims.

In the accompanying drawing, wherein a convenient embodiment of my invention is set forth,

Fig. 1 is a top plan view of one end of a shuttle made according to my invention with the weft as it appears on the first pick after transfer,

Fig. 2 is a view similar to Fig. 1, but with the weft shown as threaded through the delivery eye on the return pick after transfer,

Fig. 3 is a vertical section on line 3—3 of Fig. 2, and

Fig. 4 is a perspective view of the tension member and its coacting fixed pins or posts.

Referring to the drawing, the shuttle S has a weft chamber C to receive a bobbin B and also a tension chamber T in which the subject matter of my present invention is located. The latter chamber may be elongated in the direction of the axis of the shuttle and of appropriate depth, and communicates with the weft chamber by a throat 10. There is provided in the front wall of the shuttle a delivery eye D which connects at its rear end with the tension chamber T. An appropriate cover 11 may be secured in any manner to the shuttle and extends over a portion of the thread chamber as indicated in dot and dash lines in Fig. 1.

There is projecting upwardly from the floor of the tension chamber a pivot pin 20 around which swings a tension member or wire designated generally at 21. The latter may be formed in any way to provide a bearing surrounding the pivot and has a rearwardly extending finger 22 attached to an elastic 23 the other end of which is anchored to the shuttle as at 24. The effect of the elastic is to tend to hold the wire in the position shown in Fig. 1.

The wire is formed as shown in Fig. 4 and has upright portions 25 formed at the front of the wire. Downwardly facing hooks 26 are disposed rearwardly of the vertical portions 25. As shown in Figs. 1 and 2 there are two of these hooks and there are projecting upwardly and preferably in alignment longitudinally of the shuttle a series of guide pins 27, 28, 29 and 30, respectively. One of the hooks is positioned to move between the pins 29 and 30 while the other hook moves between the pins 28 and 29.

The end of the wire which is adjacent the throat 10 is formed of a spiral trap 31 as shown in Fig. 4, the end of the trap toward the throat having a coil of relatively small diameter, while the end toward post 28 is of a relatively large diameter.

That end of the wire opposite the spiral is bent to extend forwardly and horizontally as at 32 and then downwardly as at 33, and then upwardly to form a thread engaging actuator arm 34 bent to define a slight notch 35. The parts are related normally as shown in Fig. 1 with the arm 34 in front of the line of pins.

In the threading of the shuttle during the first pick subsequent to transfer of bobbin B into the shuttle, the weft W will extend from the bobbin chamber through the throat 10, along the series of pins and across the tension cham-

105

110

ber, and then over the end of the shuttle through an undercut groove 40. On the return pick the weft will be guided under the beak 41 of the plate and be directed downwardly against the upper part of arm 34. The shuttle may be provided with any approved form of guide slot 42 which will direct the weft toward the delivery eye D. As the weft moves down slot 42 and into engagement with the arm 34 it assumes the position shown in full lines in Fig. 2. During this return flight toward the magazine the weft is attached to the selvage opposite the magazine, and this causes the weft to pull against arm 34 and move the latter in a left hand direction as viewed in Figs. 1 and 2. The outer pin or post 30 acts as a guide pin to produce a bend in the weft as the latter leads to the arm 34. The wire is thus thrown by the weft from the full line position shown in Fig. 1 to the full line position shown in Fig. 2.

The hooks open downwardly and are so formed that they slide over the weft in their movement between the pins, thus causing the weft to lie between the hooks and the front vertical portions 25 of the wire. Also, the spiral trap 31 moves to a position behind an over the weft. As the wire swings against action of the elastic, the weft which has been located in the notch 35 moves the said arm toward a line joining post or pin 30 and the delivery eye. The tension of the weft due to continued travel of the shuttle will hold the wire substantially in the position shown in full lines in Fig. 2 until the shuttle is boxed.

Should any slackness result in the weft due to 35 rebounding of the shuttle or forward movement of the lay, the elastic will move the wire in a counter-clockwise direction around the pivot pin 20 toward the dotted line position shown in Fig. 2. When moving to this latter position the weft will be given a zigzag course as shown in dotted lines 40 in Fig. 2 because of the pins and the hooks and spiral. In addition, the weft will also be drawn toward the right end of the shuttle due to the fact that the notch 35 is moved in that direction. 45 When the hooks move to the dotted line position of Fig. 2. This movement of the notch is away from the aforesaid line joining the guide post 30 and the delivery eye, and therefore increases the path through which the weft must pass, thus affording additional take-up or draw-back for the weft.

It is found that the weft will pass around the various convolutions of the spiral 31 and will ultimately lie within all the coils. Because of this 55 fact the thread is held against displacement with respect to the hooks. The delivery eye is so placed vertically that the tendency of the weft is to move along a line above the bottom of the hooks tending in this way to prevent unlooping of the weft with respect to the hooks. The notch 35 is also preferably so related to the spiral as to hold the weft well above the bottom of the hooks.

From the foregoing it will be seen that I have 65 provided a simple form of tension which is preferably pivoted about the end thereof remote from the bobbin chamber and having a wire with hooks and a thread trap in the form of a spiral movable by a force communicated through an extension of the wire which engages the weft as the shuttle 70 is threaded. The arm has a movement which tends to draw back the weft when the elastic moves the wire to normal position. Furthermore, it will be seen that the notch 35 and spiral trap are so placed as to keep the weft well above the 75 lower ends of the hooks.

Having thus described my invention it will be seen that changes and modifications may be made therein by those skilled in the art without departing from the spirit and scope of the invention and I do not wish to be limited to the details herein disclosed, but what I claim is:

1. In a self-threading weft tension and weft pull-back for a shuttle having a delivery eye, a plurality of spaced weft engaging posts fixed to the shuttle, and two weft engaging elements secured to each other and movable about a pivot fixed on the shuttle, one of said elements having spaced thread engaging members to become engaged and threaded with the weft at points between the pins, and the other element normally in thread engaging position when the members are out of threading position to engage the weft as the latter moves toward the delivery eye to move the other element to threading position, and yielding means to move both elements in a direction to exert draw-back tension on the weft. 95

2. In a self-threading shuttle tension and weft pull-back for a shuttle having weft and tension chambers and a delivery eye, a plurality of spaced weft engaging posts fixed in the shuttle, elements 100 each to engage and tension the weft and located in the tension chamber, means normally to hold one of the elements spaced from the pins, the other element being positioned to engage the weft while the first element is spaced from and 105 out of threading relation with respect to the pins as the weft moves toward the delivery eye to move the first element toward the pins to cause said first element to become threaded with the weft, said means effective to move each element in a direction to take up slack in the weft. 110

3. In a self-threading weft tension and weft pull-back for a shuttle having a delivery eye, a plurality of spaced weft engaging posts fixed to the shuttle, a resilient element, and a swinging 115 member movable against action of the element and having two parts each to tension and pull back the weft, one part extending into the path of the weft while the other part is out of the path of the weft and effective to move the other part 120 toward the posts by a force derived from the weft, and the other part having provision for engaging the weft between the posts when said first part is moved by the weft, the resilient element to move said other part away from the posts and 125 the first part against the weft to tension and pull back the weft.

4. In a self-threading shuttle, a delivery eye for the weft, a series of spaced pins, a movable weft tensioning member having an actuating element normally in the path of the weft and movable by the weft toward a straight line connecting the delivery eye and one of the pins, means on the member movable by the actuating element between the pins to engage the weft between the pins, and a device to cause the means and element to move to deform the path of the weft. 135

5. In a self-threading shuttle, a delivery eye for the weft, a series of spaced pins, a movable tensioning member having a hook and an actuating element, the element normally positioned to be engaged by a weft extending from a pin to the eye and effective when so engaged to move the hook toward the pins by a force derived from the weft to cause said hook to engage the weft at a point between the pins, and means to move the member to cause both the hook and element to cooperate with the pins to take up slack in the weft. 140

6. In a self-threading shuttle, a delivery eye for the weft, a series of spaced pins, a movable tensioning member having a hook and an actuating element, the element normally positioned to be engaged by a weft extending from a pin to the eye and effective when so engaged to move the hook toward the pins by a force derived from the weft to cause said hook to engage the weft at a point between the pins, and means to move the member to cause the hook to coact with the pins and the element with one pin and the eye to take up slack in the weft. 80
- 10 7. In a self threading shuttle, a delivery eye for the weft, a series of spaced pins, a movable tensioning member having a spiral thread trap and an actuating element and a hook between the trap and element, the element positioned to be engaged by the weft and moved by a force derived from the latter to move the trap and hook toward the pins, causing the trap and hook to engage the weft at points spaced from the pins, and yielding means to move the member to cause the trap, hook and element to co-operate with the pins and take up slack in and tension the weft. 85
- 15 20 8. In a self-threading shuttle, a delivery eye for the weft, a series of spaced pins, a movable tensioning member having a spiral thread trap and an actuating element and a hook between the trap and element, the element positioned to be engaged by the weft and moved by a force derived from the latter to move the trap and hook toward the pins, causing the trap and hook to engage the weft at points spaced from the pins, and yielding means to move the member to cause the trap, hook and element to cooperate with the pins and take up slack in and tension the weft. 90
- 25 30 35 9. In a self-threading shuttle, a delivery eye for the weft, a series of spaced pins, a movable tensioning member having a spiral thread trap and an actuating element and a hook between the trap and element, the element positioned to be engaged by the weft and moved by a force derived from the latter to move the trap and hook toward the pins, causing the trap and hook to engage the weft at points spaced from the pins, and yielding means to move the member to cause the trap, hook and element to co-operate with the pins and take up slack in and tension the weft. 95
- 40 10. A tension element for the self-threading shuttle comprising a single piece of wire having a spiral trap at one end and an actuator arm at the other end and having a bearing and also a hook intermediate the trap and arm, the arm having a notch and the hook extending on both sides of a line joining the notch and trap. 100
- 45 11. A tension element for the self-threading shuttle comprising a single piece of wire having a spiral trap at one end and an actuator arm at the other end and having a bearing and also a hook intermediate the trap and arm, the arm having a notch and the hook extending below a line joining the notch and trap. 105
